Philip S. McLean
ATTORNEY

UNITED STATES PATENT OFFICE.

WILLIAM J. SWEENEY, OF EAST ORANGE, NEW JERSEY.

POSTER.

Application filed December 26, 1924. Serial No. 758,157.

To all whom it may concern:

Be it known that I, WILLIAM J. SWEENEY, a citizen of the United States, and a resident of East Orange, county of Essex, and State 5 of New Jersey, have invented certain new and useful Improvements in Posters, of which the following is a specification.

This invention relates to posters of the large display type used in store windows 10 and the objects of the invention are to provide simple, inexpensive and practical means for effectively supporting and displaying such posters and which will be quickly attachable to or detachable from the poster structure, enabling the poster to be displayed either as on a stand or hung on a 15 wall or other support.

The foregoing and other desirable objects are attained in this invention by certain 20 novel features of construction, combination and relation of parts as will be clear from the following specification.

In the drawings accompanying and forming part of this specification, practical embodiments of the invention are illustrated, but as such illustration is primarily for purposes of disclosure, it should be understood that the structure may be modified and changed in various respects without 30 departure from the broad spirit and scope of the invention as hereinafter defined and claimed.

Figure 1 is an edge or end view of the poster as unrolled and set up on the stand 35 provided therefor, a portion of the nearest prop being shown in section and the hook which holds it extended being indicated in broken lines in released position.

Figure 2 is a rear view indicating in 40 broken lines how when the supporting sticks are released at the top, they may be swung about their pivotal connections with the bottom of the poster for folding in a compact bundle.

Figure 3 is a view of the poster shown 45 as detached from its supports and suspended from a wall or other support.

Figures 4 and 5 are broken detail views of the prop showing the manner in which the brace or hook may be housed in a recess in the face of the prop, Figure 5 being taken on substantially the plane of line 5—5 of Figure 4.

Figure 6 is a part sectional edge view of 50 the complete device illustrating another

form of hinged brace for holding the prop extended.

Figure 7 is a further enlarged broken view showing the prop folded.

Figure 8 is a sectional plan as on line 8—8 60 of Figure 6.

Figures 9 and 10 are broken edge views of another form of invention, showing the prop in extended and in folded relation and Fig. 11 is a broken rear view of this form. 65

The poster is shown in the form of a flexible sheet 7 carrying the display matter and provided at top and bottom with edge reinforcements consisting of half round strips 8 secured together over the interposed sheet by staples 9. A loop or tab 10 caught between the strips of the upper edge reinforcement serves as a means for hanging the poster, Figure 3, when the supporting stand is not to be used. 70

The supporting stand consists of two uprights 11 braced by inclined props 12, all of which may be made of light, thin strips of wood. The uprights are detachably secured, in suitably spaced relation to the upper and lower edge strips of the poster by fastenings which, for the sake of ready releasability, may consist simply of fasteners of the "Magill" type passed through registering openings 13, 14, in the edge strips and supports respectively, with the heads 15 of such fasteners at the front of the edge strips and the split ends 16 of the fasteners bent over the backs of the supporting strips. 75

This construction makes the supports and 80 the poster practically one frame and with the proper vertical spacing of the openings in the supports, the poster is held in tightly stretched condition. If desired, a series of the fastener openings 14 may be provided in 95 the supports, allowing a certain amount of adjustment for stretching the poster and enabling the use of the supports with posters of different length.

To increase the bracing effect between 100 stand and poster and to facilitate quick positioning of the uprights, either one or both the edge strips may have vertical grooves or cuts 17 in the backs of the same to receive the upright strips. This seating of the uprights in the edge strips, in addition to bracing the parts, reduces the overall thickness of the device. 105

The props are hingedly connected at their upper ends with the uprights by strips of 110

sheet metal 18 or other sufficiently flexible material, shown as tacked or otherwise secured at their upper ends to the backs of the uprights and as secured at their lower ends 5 to the upper ends of the props by having the side edges of the same turned over so as to form in effect, sockets 19 receiving the end portions of the props. The ends of the props may be secured in these sockets as by 10 means of the tacks or fastenings 20. The props thus become a part of the uprights, being in effect attached thereto by one piece flexible hinges which permit the props to lie flat against the back of the uprights when 15 not in use, as indicated in Figure 4, and to swing outwardly under a certain degree of tension when they are to be used for support props, as in Figure 1.

To brace and hold the props in their 20 proper angular relation, struts may be employed, these being shown in Figures 1 to 5 in the form of the wire hooks 21 pivoted to loops 22 on the back of the uprights and having their free ends engaged with loops 25 23 on the inner side of the props. At their pivot ends these hooks are shown formed with upturned extensions 24 engageable with the back of the uprights when the hooks are caught to the props to exert a 30 downward spring force, tending to hold the free ends of the hooks firmly engaged in the loops 23. This requires that the free ends of the hooks be lifted against the tension of these hold-down extensions so 35 that accidental release of the hooks is made practically impossible and the parts are braced under a certain amount of spring tension.

To enable the props being folded flat 40 against the back of the uprights, one or the other of such parts may be hollowed to receive the hooks and loops described. In the illustration, Figures 4 and 5, the inside face of each of the props is hollowed out to form a recess 25 which will accommodate the hook and the loops when the parts are folded flat together.

In setting up the poster on its stand, it is 50 simply necessary to pass the four fastenings through the edge strips and uprights, spread them at the back and then swing out the props and catch them with the hooks. The structure then forms a light, well braced frame capable of supporting the largest 55 styles of posters. When collapsed, the uprights with their props occupy but small space and can be easily rolled with the poster. If desired, the upper fastenings only 60 may be detached and the braces be swung about their lower fastenings as pivots, as indicated in dotted lines, Figure 2, and the poster then be rolled to enclose the attached braces. After the poster has served its primary display purposes, it may be quickly 65 detached from the supporting frame mem-

bers and be hung up out of the way as in Figure 3, leaving the supporting elements free for use with other posters.

All parts of the device are of light, simple, inexpensive form and the construction 70 as a whole is entirely practical and efficient for the purposes intended.

In the form of the invention illustrated in Figures 6 to 8, the prop is braced open by a hinged strut made up of two sheet metal 75 hinge strips 26, 27, hingedly connected together at 28 and hinged at their other ends at 29, 30 to the support and prop respectively. The strut is thus in the nature of a leaf hinge pivotally supported at its ends 80 and folding upwardly as in Figure 7, to occupy but small space between the support and prop. To limit the downward movement of the hinge, a stop lug 31 is shown carried by the hinge piece 26 and arranged 85 to overlie the top of the companion hinge piece 27. This stop lug may be provided by that part of the end of the hinge plate 26 intermediate the hinge knuckles 32 at the edges of such plate and which is displaced 90 upwardly to provide space for the hinge loop 33 on the other hinge plate which enters between the knuckles 32. This intermediate strip would ordinarily be removed but by bending it upward and allowing it to extend forwardly beyond the end of the hinge plate, it provides a stop and is preferably so located as to permit the hinge center 28 to pass slightly down beyond a line between the end pivots 29 and 30 so that the strut 100 will lock in the nature of a toggle.

In Figures 9, 10 and 11 the braces or props 12 are flexibly connected with the uprights 11 by spring hinge strips 18' which are doubled into reverse U form so as to exert a tendency to swing the braces open. Such opening movement is limited in the illustration by flexible cords 33' secured in some way between the braces and props and shown as simply passed through openings 110 34 and knotted at 35. These flexible connections provide a simple, inexpensive means for limiting the spreading of the props and when the props are folded against the back of the uprights, they may be utilized 115 to secure the props in this relation by simply wrapping the cord about the two, as indicated in Figure 10.

What is claimed is:

1. In combination, a flexible poster having edge strips at top and bottom of the same, the upper edge strip being perforated near the ends for passage of fastenings, light supporting strips at the back of the poster perforated at their upper ends, readily releasable fastenings detachably engaged in the perforations in said supporting strips and the upper edge strip, whereby the supports are detachably secured to the upper edge of the poster, said supporting strips 120

125

130

- being sufficiently longer than the poster to support said poster with the lower edge strip clear of the floor or other support, fastenings detachably holding said lower edge strip to the lower portions of the supporting strips and a prop for the supports having a swinging mounting and provided with means for pressing the same in extended relation.
- 10 2. In combination, a flexible poster having edge reinforcements, supports for the poster, releasable connections between the supports and edge reinforcements, props for said supports and one piece resilient spring hinge strips arranged in reverse U-form, connected with the upper ends of the props and the backs of the supports and connections from the supports engaged by outwardly swinging portions of the props to limit the extension of the props.
- 15 3. In combination, a flexible poster having edge strips at top and bottom of the same perforated near the ends for passage of fastenings, one piece supporting strips perforated near their opposite ends to register with the perforations in the edge strips when the poster is unrolled and extended, readily releasable fastenings detachably engaged in the registered perforations in the supports and edge strips, prop means for supporting the poster, a spring connection between said prop means and the supporting strips for automatically extending the same and means for limiting the automatic extension of the prop means when the poster is set up, said limiting means being foldable with the poster and the spring mounting enabling the prop means to yield into folded relation to the supports when the poster is folded.
